UNITED STATES PATENT OFFICE.

ABEL S. LINDQUIST, OF SPRINGDALE, PENNSYLVANIA.

ATTACHMENT FOR COMBINATION-SQUARES.

1,273,510.

Specification of Letters Patent. Patented July 23, 1918.

Application filed September 2, 1914. Serial No. 859,900.

To all whom it may concern:

Be it known that I, ABEL S. LINDQUIST, a citizen of the United States, and resident of Springdale, in the county of Allegheny 5 and State of Pennsylvania, have invented a new and useful Improvement in Attachments for Combination-Squares; and I do hereby declare the following to be a full, clear, and exact description thereof.

10 My invention relates to a new and improved attachment for a so-called combination square, which is particularly though not exclusively adapted for use in the laying out of key-ways or grooves for shafts 15 and the like.

The object of the invention is to provide a simple and economical device which may be readily applied to the ordinary combination squares now in general use. A further 20 object is to adapt the device for use with squares of different sizes, and for determining the line of milling or boring on shafts of different diameters. A further object is to so construct the device that it may be 25 used independently of the square for tapping an indicating mark on a shaft, tube or other metal article.

With these objects in view, the invention consists in the construction and arrangement of parts, a preferred embodiment of 30 which is illustrated in the drawings herewith in which Figure 1 is a combination square with my device applied thereto; Fig. 2 is a view of the centering head detached 35 from the square; Fig. 3 is a perspective view of my improved centering punch; Fig. 4 is a view or modified form thereof which may be used with or independently of the square; and Fig. 5 is a horizontal sectional 40 view taken on the line 5—5, Fig. 1.

Referring to Fig. 1, 1 indicates the blade of an ordinary square, 2 indicates the centering head, which is attached to the blade in the usual manner and secured in position 45 by set nuts 3 in the manner common to these tools. The blade 1 is also fitted with the usual right-angle or tri-square head 4 having embodied therein the spirit level 5. In instruments of this character as usually employed for determining the position of key-ways or borings on a shaft, the centering punch of the completed structure is frequently a permanent part of the tool, and is frequently in the way when the tool is 50 to be used for other purposes. In accordance with my invention on the other hand,

the centering punch is readily detachable from the tool as a whole, and furthermore, utilizes the usual structure of the tool as a means for holding it in position thereon. 60 Specifically, my invention comprises a prick punch 6, which slides more or less freely in a sleeve 7. This sleeve is provided with a series of longitudinal grooves 8, 9, 10, and 11, by which the punch is mounted 65 on the centering head 2 thereof by engaging one of these grooves with the usual strengthening rib 12 of the centering head. The lower ends of the grooves of the sleeve are cut away at 13 to fit the flanges 14 of 70 the arms of the centering head so that when the sleeve is held by the operator's thumb in position on the centering head, it is invariably accurately alined in relation to the apex of the angle at the junction of the 75 arms of the centering head 2. In order that the device may be used with squares of different sizes and in which the strengthening ribs 12 are used in different thicknesses, the 80 several grooves 8 to 11 inclusive of the sleeve differ in width according to these different thicknesses of the strengthening ribs so that the device may be employed with combination squares or with the centering heads thereof of several different sizes. 85

In the use of the device, one of the grooves of the sleeve is seated on the strengthening rib 12 of the centering head, and the diverging faces at the lower end of the groove are seated upon the ribs 14 of 90 the arms of the head; this brings the point of the prick punch 6 exactly in alinement with the blade of the square, and in a position bisecting the angle between the arms of the centering head 2. If now the arms 95 of the centering head are rested upon a shaft, tubing, or the like, and the square is shifted until the spirit level shows the exact horizontal position, the prick punch, which slides sufficiently freely in the sleeve 7, may 100 be tapped to produce the necessary indicating prick point on the shaft or the like. The tool may be then shifted to another position on the shaft where a key-way in alinement with the first key-way is to be 105 formed and a second indicating prick point produced. Also, where it is desired to bore a series of holes in the shaft or the like in alinement, the tool may be shifted to the desired points and the indicating marks 110 produced as described.

It will be seen, therefore, that my im-

proved attachment is adapted for use primarily with a combination square and centering device as described, and for use with a series of squares of different sizes. Furthermore, the device is only held in position on the square by the hand of the operator, and it may be readily detached and laid aside when it is desired to use the square without it.

- 10 In the embodiment of the device illustrated in Fig. 4, it may also be used as a prick punch entirely independent of the square, and in this form, the operator may dispense with a hammer or other implement for tapping the prick punch 15. In this case, the sleeve 16 may be of the structure heretofore described, but the prick punch is provided with a collar or shoulder 17 near its pointed end, and sufficiently near thereto not to limit materially its use upon shafts or rods of small diameter when it is desired to use this device with a square or centering head. In this form of the device illustrated in Fig. 4, the point of the prick punch may be placed at the point of the work where it is desired to make an impression with the sleeve 16 lifted above the collar 17. The sleeve may then be slid quickly down upon the collar 17 and by its own 30 weight cause the point to prick the desired indicating mark.

While I have described a particular embodiment of my invention, it is to be understood that it may be varied in details of structure and in the relative arrangement of parts within the scope of the appended claims.

What I claim is:

1. In a centering device, the combination 40 with a blade equipped with a centering head and a spirit level located at a substantial distance from said head, of a prick punch slidably mounted in a short sleeve, said sleeve having means to position it accurately in engagement with said centering head.

2. In a centering device, the combination 50 with a blade having a centering head adjacent one end thereof, and having a spirit level adjustably mounted on said blade, said head having a strengthening rib cast thereon, and a prick punch slidably mounted in a sleeve, said sleeve being grooved to engage

said rib whereby said prick punch may be positioned and held accurately on said head. 55

3. In a centering device, the combination with a blade, having a centering head adjacent one end thereof, and having a spirit level mounted on said blade, of a detachable prick punch slidably mounted in a sleeve, 60 said centering head having a rib extending from the apex of the angle thereof, and said sleeve having a groove adapted to fit said rib accurately to accurately position the prick punch with respect to said head, 65 said sleeve having additional grooves of different cross-section to fit centering heads of different sizes.

4. A prick punch to be used with a centering head, and comprising the punch proper, a sleeve within which said punch is slidably mounted, said sleeve having grooves and recesses adapted to fit complementary parts respectively of centering heads of different sizes. 70

5. A prick punch comprising a punch proper, having a shoulder near the point thereof, and a weighted sleeve slidably mounted on said punch whereby when said punch point is positioned, said sleeve may be slid quickly against said shoulder to cause said point to produce an impression, said sleeve having guide surfaces whereby said punch may be accurately positioned on a centering-head. 80

6. A prick punch comprising a punch proper, having a shoulder near the point thereof, and a weighted sleeve slidably mounted on said punch whereby when said punch point is positioned, said sleeve may be slid quickly against said shoulder to cause said point to produce an impression, said sleeve also having longitudinal grooves of different cross-area whereby said device is adapted to be used in conjunction with 95 centering heads having complementary parts to fit said grooves, said parts also being of different cross-section according to the sizes of the centering heads respectively.

In testimony whereof I the said ABEL S. 100 LINDQUIST have hereunto set my hand:

ABEL S. LINDQUIST.
